ILLINOIS.

HOG RING AND THE LIKE.

Application filed August 6, 1927. Serial No. 211,201.

The present invention relates to certain improvements in hog rings and the like, and these improvements are intended especially for preventing the hog from catching fowl such as chickens, and for so interfering with rooting and other objectionable actions such as attempting to lift gates, that the hog will be effectively discouraged therefrom. At the same time, the device herein disclosed is so arranged that it will not materially interfere with proper feeding, and will therefore not be objectionable from this standpoint.

Generally stated, the invention consists in the provision of a depending member which is so pivoted from the ring which engages the nose or snout that said depending member will strike the ground and thus stop the lowering of the hog's snout before the hog can bite into or take hold of the fowl or other moving object. These depending members are of sufficient length to accomplish the foregoing object, and they are pivoted freely on the ring itself so that they will naturally fall into the vertical or interfering position and will thus strike the ground at a point immediately in advance of the hog. However, when the hog throws his snout suddenly forward the depending members will be cast forward, so that the hog can then draw his snout rearwardly, and by so doing the depending members will be dragged backwardly and will not strike the ground in a direct vertical fashion, with the result that they will extend down at such an angle that they will not interfere with normal feeding. In other words, by such action the hog can easily feed on corn cobs or other normal feed, and without interference from the depending members.

Whenever the hog runs after a fowl or other moving object the members will depend in vertical fashion, and due to the fact that the hog must throw his snout directly down to catch such running fowl, it will be impossible for him to so manipulate the depending members as to be able to catch the fowl in his snout. Thus the desired object will be accomplished, and sufficient interference will be created to prevent catching fowl or other moving objects, but normal feeding will not be prevented.

This arrangement will also prevent the hog from getting his snout beneath the gate or other object which he would otherwise

lift, because it will be impossible for him to throw the depending members far enough forward to allow him to lower his snout the necessary extent. The depending members will also accomplish other desirable and useful results.

A further object is to provide an arrangement whereby the hog ring may be clamped to the snout of the hog in the usual manner, and by the use of a clamp or tool such as is in general use today for similar work. Also to provide an arrangement such that, if desired rings of the present and well known form may be used, the member or members being placed thereon; or, if desired, rings of new and improved form may be substituted, which will tend to hold the depending members in better centered position than otherwise.

A further object is to provide an arrangement such that when the ring itself is cut in order to remove it from the snout of the hog, as when the hog is marketed, the depending member or members may be recovered and again used in connection with a ring to be applied to another hog. In this way the loss will be greatly reduced, and the device may be used over and over again.

A further object of the invention is to provide an arrangement such that it can be easily and cheaply made from sheet or bar metal, and by the use of simple manufacturing processes, thereby greatly reducing the cost of manufacture, and also adapting the invention to manufacture by simple and well understood processes.

Other objects and uses of the invention will appear from a detailed description of the same, which consists in the features of construction and combinations of parts hereinafter described and claimed.

In the drawing;

Fig. 1 shows a side elevation of a device embodying the present invention, part thereof being in section so as to better reveal the construction;

Fig. 2 shows a fragmentary side elevation corresponding to Fig. 1; and

Fig. 3 shows a fragmentary view similar to that of Fig. 1, but with the ring closed or clamped shut in the manner usual when applying the rings to the hog's snout.

The ring proper is designated by the numeral 5. It is usually made of somewhat elliptic form, with its ends 6 and 7 sep-

arated a sufficient distance to allow for ready application to the hog's snout. Furthermore, these ends are generally pointed, as shown. When the ring is applied to the snout, it is clamped together, as shown in Fig. 3 so as to bring the points into substantial engagement, or at any rate so as to sufficiently engage the snout to prevent removal of the ring except with the intention of the farmer. Usually, also these rings are of plain form, and when they are clamped together they are substantially circular.

According to our present invention we provide a depending member which may be applied to the ring, and which when so applied will hang down freely, and will always fall into substantially vertical position. This depending member or members is sufficiently long to cause its lower end to strike the ground before the hog can take an object into his mouth. Thus, for example, the member is sufficiently long to strike the ground before the hog can catch hold of a chicken or other fowl.

The preferred arrangement is that illustrated in the figures. It comprises a pair of prongs 8 and 9 which have their upper ends pivotally mounted on the ring 5, and which prongs are supported with sufficient freedom to allow them to swing naturally into the vertical position, pivoting for this purpose on the ring itself. The prongs are also preferably so arranged that they extend outwardly from each other at an angle of substantially 50 degrees as shown. Also the lower ends of the prongs are preferably pointed so that they will not easily slip along the surface of the ground or floor.

In order to permit the prongs to swing with the greatest freedom of movement, they preferably have their upper ends bent at a complementary angle so that said upper ends will pass across the ring at right angles as illustrated in Figs. 1 and 3. That is to say, the upper ends of the prongs lie in a vertical position while the ring crosses them horizontally at the pivoting point. Preferably, also, both of the prongs are made from a single piece of metal stock, as for example a bar or rod. Then said bar is bent so as to establish the upper pivoting end section 10, which has sufficient length to allow for the desired pivoting action. This result is accomplished by so bending the bar that it is folded directly together in its upper end section, and then its prongs portions are flared outwardly at the desired angle.

The upper pivoting end of the member 10, is perforated at 11 to accommodate the ring, and this perforation is of sufficient size to allow for the desired freedom of swinging movement on the ring.

In order to prevent the depending member from shifting sidewise on the ring, and to ensure proper centering action at all

times, it may sometimes be desirable to establish an offset section of the ring as at 12, said offset portion having the proper amount of offset to substantially prevent lateral shifting, but not enough offset to prevent easy application of the depending member to the central portion of the ring in the first instance. Furthermore, it will generally be found that when the ring is clamped together into the form of Fig. 3, the amount of offset will increase slightly, so that in operation the depending member will be properly centered even with only a slight amount of initial offset.

It will be noted that with the arrangement herein disclosed, the depending member may be used over and over again, by simply removing the same from the ring after the latter has been removed from the snout of one hog, and then placing the depending member on another ring to be used on another hog.

While we have herein shown and described only a single form of our invention, still we do not intend to limit ourselves to the same except as we may do so in the claims. Furthermore, we do not limit ourselves to any particular sizes or material for the construction of the device, since manifestly these will be a matter of selection according to circumstances.

We claim:

1. In a device of the class described, the combination of a ring adapted for engagement with the snout of a hog, said ring comprising a curved member having its ends in-turned towards each other and pointed, and having its central portion provided with an offset which extends outwardly from the general curvature of the ring and acts as a seat for the prong member, and a prong member freely pivoted on said offset portion of the ring, and comprising a section of rod bent to establish two relatively long prongs united at the central portion, and flaring outwardly from each other at an angle of substantially fifty degrees, the central portion of said prong member comprising a straight section of double thickness extending in a direction to substantially bisect the angle between the prongs, the ends of the prongs being sharpened, and the straight section aforesaid being perforated with a hole of sufficient size to freely accommodate the offset portion of the ring, and to allow the prong member to swing freely thereon, substantially as described.

2. In a device of the class described, the combination of a ring adapted for engagement with the snout of a hog, said ring comprising a curved member having its ends in-turned towards each other, and having its central portion provided with an offset which extends outwardly from the general curvature of the ring and acts as a seat for

the prong member, and a prong member freely pivoted on said offset portion of the ring, and comprising a section of rod bent to establish two relatively long prongs united 5 at the central portion, and flaring outwardly from each other, the central portion of said prong member comprising a straight section of double thickness extending in a direction to substantially bisect the angle between 10 the prongs, and the straight section aforesaid being perforated with a hole of sufficient size to freely accommodate the offset portion of the ring, and to allow the prong member to swing freely thereon, substantially as described.

3. In a device of the class described, the combination of a ring adapted for engagement with the snout of a hog, said ring comprising a curved member having its ends 20 inturned towards each other, and having its central portion provided with an offset which extends from the general curvature of the ring and acts as a seat for the prong member, and a prong member freely pivoted on said offset portion of the ring, and comprising a member having a pair of arms which reach outwardly from a central portion at an angle of substantially fifty degrees 25 to each other, the central portion of said

member being substantially straight, and 30 reaching backwardly in a direction to substantially bisect the angle between the arms aforesaid, and said straight portion being perforated with a hole of sufficient size to 35 freely accommodate the offset of the ring and allow the prong member to swing freely thereon, substantially as described.

4. In a device of the class described, the combination of a ring adapted for engagement with the snout of a hog, said ring comprising a curved member having its ends 40 inturned towards each other, and a prong member freely pivoted on the ring, and comprising a member having a pair of arms which reach outwardly from a central portion at an angle with respect to each other, the central portion of said member being substantially straight, and reaching 45 backwardly in a direction to substantially bisect the angle between the arms aforesaid, and straight portion being perforated with a hole of sufficient size to freely accommodate the ring and allow the prong member to swing freely thereon, substantially as described.
